UNITED STATES PATENT OFFICE.

WILLIAM Y. DONAHOE, OF CASCADE, IOWA.

BREECH-LOADING ORDNANCE.

No. 901,781.

Specification of Letters Patent. Patented Oct. 20, 1908.

Application filed November 19, 1907. Serial No. 402,835.

To all whom it may concern:

Be it known that I, WILLIAM Y. DONAHOE, a citizen of the United States, residing at Cascade, in the county of Dubuque and State of Iowa, have invented certain new and useful Improvements in Breech-Loading Ordnance, of which the following is a specification.

My invention relates to breech-loading ordnance.

10 The objects of my invention are to provide an improved breech-block; to provide improved means for locking and unlocking the breech-block within the breech; and to provide an improved breech-block adapted to be used in conjunction with electrical means for igniting the cartridge of the projectile.

15 My invention, generally stated, comprehends a breech-block having a desired number of depressible members adapted to normally project beyond the outer surface of the breech-block and engage grooves formed in the breech for the purpose of locking the breech-block therein: the form of the grooves 20 being such that the rotation of the breech-block ejects the depressible members from the grooves in the breech thus unlocking the breech-block.

25 My invention contemplates further, a breech-block formed with a channel along its outer surface adapted to receive an electrical conductor carried by the cartridge-case of the projectile.

30 In the following description and claims, and in the accompanying drawings, I have indicated a preferred embodiment of my invention for accomplishing the foregoing and hereinafter indicated objects: I however reserve the right to make any modifications 35 thereto that fall within the scope of my invention.

35 In the drawings—Figure 1 is a longitudinal vertical section showing my breech-block, partially in section, in a locked position 40 within the breech; and showing also, in elevation, the projectile, its connected cartridge-case, and the electric conductors carried thereby. Fig. 2 is a transverse section on the line A—A of Fig. 1. Fig. 3 is a perspective view of the breech-block.

45 1 indicates a portion of a gun, 2 the breech thereof 3 a cylindrical breech-block chamber therein, and 4, the breech-block.

50 The breech-block is provided with pawls 5, one or more as the size of the breech-block requires, which are housed in recesses 6

formed in the breech-block, and are pivoted on pins 7 fixed therein. The free end of each pawl is normally projected beyond the outer surface of the breech-block for the purpose of engaging the sides of a groove 8, formed in the wall of chamber 3. The lowermost pawl, the one shown in full lines in Figs. 1 and 2, is thus projected by gravity; but the other pawls are provided with springs 9 for this purpose.

55 The grooves 8 are preferably formed with a shoulder 10 defining one end thereof; and from this shoulder the groove decreases in depth until it merges into the chamber 3.

60 The breech-block may be provided with an exterior or peripheral groove or channel 11. This channel is adapted to receive an electric conductor 12, carried by the cartridge-case 13 of a projectile 14, the conductor being 65 adapted to convey an igniting charge of electricity to the forward end of the cartridge upon the closing, in any suitable manner, of the electric circuit.

70 The block 4 is preferably provided with 80 handles 15.

75 The operation of my device is as follows: The projectile, with the cartridge connected thereto, is positioned in the gun, the conductor 12 projecting beyond the rear of the breech. A portion of this conductor, beyond the cartridge-case, is then placed in the channel 11 of the breech-block; and the latter is inserted in its chamber 3 in proper position to have the pawls 5 engage the sides 85 of the grooves 8 near the shoulders 10 thereof. This proper positioning of the block may be readily accomplished by any suitable registering of marks or points on the breech-block and breech. This engagement of the 90 grooves in the breech by the pawls locks the breech-block in position; and the projectile may be then fired by closing the circuit. When it be desired to open the breech, the breech-block is rotated clock-wise, see Fig. 2, 95 and the decreasing depth of the grooves 8 forces the pawls backwards into their recesses 6, this backward movement of the pawls continuing until they pass out of the grooves 8, whereupon the breech-block is unlocked and may be withdrawn.

100 The number of pawls to be carried by a breech-block is determined by the size of the latter. In Fig. 1, one pawl is shown in full lines and another in dotted lines; and in Fig. 2 four pawls are shown.

105 The rearward strain upon the pawls, when

in use, can in a great measure be taken up by the forward end of the pawls, the ends opposite the free ends, engaging the rear ends of their recesses.

5 My invention has been shown applied to a breech-block the size of which permits its manual insertion into and withdrawal from the breech. It is obvious, however, that if desired, it can be applied to ordnance the 10 breech-block of which is of a size that requires mechanical means for its movements. In such a case, the breech-block may be inserted into its chamber, rotated therein to unlock it, and removed therefrom by any 15 suitable mechanism for moving a breech-block into and out of a breech, and for rotating it therein.

When necessary, any suitable means for forming a gas-tight connection may be used 20 with my breech-block.

Having thus described my invention, what I claim is—

1. The combination with a rotatable breech-block, of a locking member carried by the 25 block and movable therein a portion of the locking member normally projecting outward beyond the surface of the block, and a breech having a breech-block chamber and having also a groove to receive the projecting portion of the locking member.

2. The combination with a breech-block, 30 of a pawl pivoted thereto, and a breech having a breech-block chamber and having also a groove in the wall of said chamber the pawl being adapted to automatically engage the groove wall to lock the block in its chamber when inserted therein the pawl being also adapted to be disengaged by the breech-block from locking engagement with the 40 breech.

3. The combination with a breech-block, 35 of a spring-actuated member carried by the breech-block, and a breech having a breech-

block chamber and having also a groove intersecting the wall of the chamber and adapted to receive a portion of the spring-actuated member the groove formation ejecting the spring-actuated member therefrom upon the rotation of the breech-block in its chamber.

4. The combination with a breech-block, of a plurality of pawls seated in recesses therein and pivoted to the breech-block, springs normally projecting the free ends of the pawls outward beyond the surface of the breech-block, a breech having a chamber therein for the reception of the breech-block and having also grooves intersecting the walls of the chamber the grooves decreasing the depth towards one end and being adapted to receive the free ends of the pawls, and hand-grasps for the breech-block, the breech-block being adapted to be unlocked by rotating it in the direction of the decreasing depth of the grooves.

5. In a breech-loading gun adapted to use electrically ignited cartridges having conductors attached thereto and adapted to convey an igniting charge of electricity to the cartridge, a breech-block having a peripheral channel adapted to receive the electric conductor and to permit a portion thereof to extend beyond the rear portion of the breech-block.

6. The combination with a rotatable breech-block, of a pawl pivoted thereto the free end of the pawl projecting normally outward beyond the periphery of the block, and a breech having a breech-block chamber and having also a transversely extending groove to receive the free end of the pawl.

In testimony whereof I affix my signature in presence of two witnesses.

WILLIAM Y. DONAHOE.

J. B. SKAHILL,
J. J. FAGAN.

Corrections in Letters Patent No. 901,791.

It is hereby certified that in Letters Patent No. 901,791, granted October 20, 1908, upon the application of William Y. Donahoe, of Cascade, Iowa, for an improvement in "Breech-Loading Ordnance," errors appear in the printed specification requiring correction, as follows: In line 58, page 2, the word "walls" should read *wall*, and in line 59, same page, the word "the" should read *in*; and that the said Letters Patent should be read with these corrections therein that the same may conform to the record of the case in the Patent Office.

Signed and sealed this 17th day of November, A. D., 1908.

[SEAL.]

C. C. BILLINGS,
Acting Commissioner of Patents.
